W. O. JARRETT,
HEATER FOR BATHTUBS, LAUNDRY TUBS, OR THE LIKE,
APPLICATION FILED JUNE 9, 1920.

1,389,050.

Patented Aug. 30, 1921.

INVENTOR
WALTER OLIVER JARRETT
BY ATTORNEY

E.H. Bond

UNITED STATES PATENT OFFICE.

WALTER OLIVER JARRETT, OF TORONTO, ONTARIO, CANADA.

HEATER FOR BATHTUBS, LAUNDRY-TUBS, OR THE LIKE.

1,389,050.

Specification of Letters Patent. Patented Aug. 30, 1921.

Application filed June 9, 1920. Serial No. 387,685.

To all whom it may concern:

Be it known that I, WALTER O. JARRETT, a citizen of the Dominion of Canada, residing at Toronto, in the county of York and 5 Province of Ontario, Canada, have invented certain new and useful Improvements in Heaters for Bathtubs, Laundry-Tubs, or the like, of which the following is a specification.

10 This invention relates to improvements in heaters for bathtubs, laundry tubs or the like. The object of my invention is to provide a heater adapted to support the bathtub or laundry tub and heating elements in the same 15 for heating the bottom of the tubs and means for controlling the said heat.

With these and other objects in view, the invention consists in the construction, combination and arrangement of parts as will be 20 hereinafter fully described, illustrated in the accompanying drawings, and pointed out in the claim hereunto appended.

Figure 1 illustrates a bathtub part in section constructed in accordance with my invention where the heating element is for gas, and

25 Fig. 2 is a perspective view of a laundry tub constructed in accordance with the preferred embodiment of my invention where the heating element is electricity.

Referring to the drawings like numerals designate like parts in the various drawings.

Referring more particularly to Fig. 1, 3 indicates the ordinary shaped bath having 30 water inlet pipes and water outlet pipes constructed in the ordinary way. This bath is supported in a heating chamber 4 which is mounted on legs 5. The heating chamber is provided with a bottom 6, sides 7 and the end 35 8, the latter being extended upwardly at an angle similar to the angle of the end of the bath 3. The angle end of the bath fits upon the angle end of the heating chamber and is pressed down until tightly fitted into the top 40 of the heating chamber 4. The heating chamber is provided with suitable heating elements, which elements can either be gas connections as shown in Fig. 1 or electric elements as shown in Fig. 2. In either case

the heating elements are controlled by the 50 controlling means 10 on the outer side of the heating chamber.

Referring more particularly to Fig. 2, 11 indicates a laundry tub of the usual construction having all four sides tapering upwardly 55 at an angle. In this case the heater has its sides tapering upwardly at a corresponding angle, so that the bottom of the laundry tub will fit only a short distance into the top of the heating chamber 4, thus causing a tight 60 connection so as to hold the heat under the laundry tub 11. In this illustration I show electric elements in the heating chamber 4 with a suitable electric cord connection 12.

From the above description accompanied 65 by the appended drawings, it will be seen that there will be no lost energy of heat and that the bath or laundry tub will be heated so as to hold the heat in the water therein instead of allowing the water to heat the tub 70 and radiate therefrom.

From the foregoing it is thought that the construction of my invention will be clearly understood, and, therefore, a more extended explanation has been omitted.

75 What I claim as new, is:—

An elongated heating chamber, means for supporting the same, heating elements within said heating chamber with a plurality of controlling means therefor, and a bath-tub independent thereof and frictionally retained therein and provided with inlet and outlet pipes, said bath-tub being detachably fitted within the heating chamber and the said heating chamber having one end extended 80 upwardly at an inclination, the other end being substantially vertical, and the ends of the bath-tub being correspondingly inclined and vertical, whereby the weight of the bath-tub tends to wedgely hold the same within the 85 heating chamber.

In testimony whereof I affix my signature in the presence of two witnesses.

WALTER OLIVER JARRETT.

Witnesses:

H. C. O'DELL,
J. H. PARKER.
